UNITED STATES PATENT OFFICE

132,201

DESIGN FOR A PHONOGRAPH RECORD RACK

Frank D. Slough, Mentor, Ohio

Application February 8, 1940, Serial No. 90,124

Term of patent 14 years

To all whom it may concern:

Be it known that I, Frank D. Slough, a citizen of the United States, residing at Mentor, in the county of Lake and State of Ohio, having invented a new, original, and ornamental Design for Phonograph Record Racks, of which the following is a specification, reference being had to the accompanying drawing, forming a part thereof, in which:

Fig. 1 is a perspective view of a phonograph record rack showing my new design, and
Fig. 2 is a top plan view thereof.

I claim:

The ornamental design for a phonograph record rack, substantially as shown.

FRANK D. SLOUGH.
